UNITED STATES PATENT OFFICE.

CHARLES A. DAVIS, OF WASHINGTON, DISTRICT OF COLUMBIA.

DESIGN FOR AN UMBRELLA-HANDLE.

SPECIFICATION forming part of Design No. 19,521, dated December 24, 1889.

Application filed November 25, 1889. Serial No. 331,557. Term of patent 14 years.

To all whom it may concern:

Be it known that I, CHARLES A. DAVIS, a citizen of the United States, residing at Washington, in the District of Columbia, have invented a certain new and original Design for Umbrella Handles or Sticks, of which the following is a specification.

My invention consists in a novel design for the handles or sticks of umbrellas, parasols, sunshades, &c., which is represented in the annexed photographs, Figures 1 and 2 showing opposite sides or faces of a handle embodying the design.

To avoid repetition I shall use the term "umbrella" in its broadest significance, or as including all that class of shades or screens designed to be carried in the hand to protect the person against the rays of the sun or against rain, snow, &c.

The design comprises the usual handle A, from which the "stick" B extends a proper distance to receive the "frame," said handle

A being formed with a series of ridges and depressions a and b, conforming more or less closely to the fingers and thumb of the hand when the handle is grasped thereby, and with an irregular face c, corresponding to the contour of the palm of the hand.

The distinguishing feature of the design may best be described by stating that its appearance to the eye is that of a plastic body which has been grasped by a human hand and firmly pressed or squeezed, leaving the imprint of the hand.

Having thus described my invention, I claim—

The design for umbrella-handles herein described and shown.

In witness whereof I hereunto set my hand in the presence of two witnesses.

CHARLES A. DAVIS.
